Bryant & Lowey ATTORNEYS.

UNITED STATES PATENT OFFICE.

JOHN KRC, OF WALLIS, TEXAS.

SPRAYER ATTACHMENT FOR HOSE NOZZLES.

Application filed July 19, 1927. Serial No. 206,994.

This invention relates to certain new and useful improvements in sprayer attachments for hose nozzles.

The primary object of the invention is to provide a sprayer attachment for hose nozzles of the type employed for spraying an insecticide or the like on growing plants, more particularly cotton and the object of the sprayer attachment is to cause the fluid flowing through a perforated nozzle to be sprayed in a relatively fine film over increased areas for the spraying of a plurality of rows of growing plants.

A further object of the invention is to provide a sprayer attachment for hose nozzles wherein the outlet end of the nozzle is of semi-circular formation with a single row of spray perforations formed in the curved side of the head, the sprayer attachment being of semi-circular formation and adjustably attached to the spray head of the nozzle in a manner to cause the sprayed film of fluid to issue in different directions from the spray nozzle which varies the area being sprayed.

With the above and other objects in view that will become apparent as the nature of the invention is better understood, the same consists in the novel form, combination and arrangement of parts hereinafter more fully described, shown in the accompanying drawing and claimed.

In the accompanying drawing wherein like reference characters are employed to designate corresponding parts throughout the several views,

Figure 1 is a side elevational view of a valve controlled hose nozzle, the nozzle head being in the form of a semi-circular chamber with a line of spray perforations in the curved side thereof and further showing the spray plate supported on the nozzle head in proximity of the line of perforations for longitudinal and transverse adjustment;

Figure 2 is a fragmentary longitudinal sectional view taken on line 2-2 of Figure 1, showing the manner of adjustably mounting the spray plate in longitudinal and transverse directions with respect to the spray nozzle;

Figure 3 is a cross-sectional view taken on line 3-3 of Figure 1 showing the screen filtering plate in the spray nozzle.

The spray nozzle disclosed in this application being intended for spraying insecticides or the like over growing plants such as cotton,

the hose 1 is in communication with a source of supply under pressure of the desired fluid, the hose 1 communicating with the control valve 2 that has a fitting 3 attached thereto which carries the nozzle 4. The valve 2 controls the flow of the insecticide to the nozzle 4.

The fitting 3 is enlarged at its outer end and externally threaded while the inner end of the nozzle 4 is provided with an annular flange 5 that carries an internally threaded collar 6 that is engaged with the threads upon the adjacent end of the fitting 3 for securing the nozzle to the fitting.

As shown in Figures 2 and 3, a filtering screen 7 is interposed between the fitting 3 and nozzle 4 and is retained in position by the gasket 8.

The nozzle 4 tapers toward its outer end and carries a discharge head 9 in the form of a hollow chamber that is semi-circular in plan view with the curved side thereof being forwardly positioned, while the curved side of the discharge head 9 is provided with a single row of perforations 10 extending the entire length of the curved side and substantially midway between the upper and lower edges thereof.

A sprayer attachment is adjustably connected to the nozzle head 9 in a manner to cause the jets of fluid issuing from the nozzle head to contact therewith and to be sprayed in the form of a relatively thin film. The sprayer attachment comprises an arcuate plate 11 with the curved inner side thereof disposed adjacent the curved outer side of the nozzle head 9, the arcuate plate 11 being carried by a curved bracket arm 12 having a forked depending leg extension 15 that is clamped by nut and bolt 18 to an angle leg 16 depending from the arm 13 indicated by dotted lines in Figure 2 that is disposed in contact with the lower side of the nozzle head 9 and retained in position by the adjusting screw 14 passing through the fork and threaded into the head.

In this form of the invention, the spray plate 11 is adjustable vertically of the nozzle head 9 and also toward and away from the same, this adjustment being provided by the screw 18 passing through the slot in the leg 15 and threaded through the part 16.

With the spray plate 11 positioned as illustrated in Figure 1, the jets of fluid issuing through the perforations 10 in the nozzle head contact the plate 11 and the plurality of

jets are converted into a relatively thin film that is sprayed over a comparatively wide area. By adjusting the spray plate 11 with respect to the nozzle head 9, the separate jets issuing through the nozzle perforations contact the sprayer plate at different points to cause a greater or lesser throw of the converted film. With a device of this character, a continuous sheet of insecticide or like fluid is sprayed over a greater area than would be possible with the use of a perforated nozzle alone as the plate attachment converts the separate jets into a thin film resulting in a continuous sheet of the substance being sprayed.

While there is herein shown and described the preferred embodiment of the present invention it is nevertheless to be understood that minor changes may be made therein without departing from the spirit and scope of the invention as claimed.

What I claim as new is:—

In a device of the class described, a spray nozzle, an enlarged chambered head of semi-circular formation having a row of perforations in the forward curved side thereof, an arcuate spray plate carried by the head against which the separate spray jets are caused to impinge to convert the jets into a film, and an adjustable connection between the spray plate and nozzle head to vary the position of the spray plate relative to the head perforations comprising an angle member connected to the nozzle head and adjustable longitudinally thereof and a bracket connected to the angle member and adjustable vertically thereof whereby the spray plate is shifted in two directions relative to the head perforations to produce sprays of different characteristics.

In testimony whereof I affix my signature.

JOHN KRC.
